UNITED STATES PATENT OFFICE.

GEORGE N. ABBEY, OF BOULDER, COLORADO, ASSIGNOR OF ONE-HALF TO M. F. MORELAND, OF DENVER, COLORADO.

UPHOLSTERING MACHINE.

Application filed September 16, 1924. Serial No. 737,976.

To all whom it may concern:

Be it known that I, GEORGE N. ABBEY, a citizen of the United States, residing at Boulder, county of Boulder, and State of Colorado, have invented certain new and useful Improvements in Upholstering Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to improvements in machines for upholstering.

In the manufacture of cushions for furniture and bed mattresses, considerable difficulty is usually experienced in introducing 20 the stuffing material into the casings. This is especially true where spring assemblies are used as in overstuffed cushions.

It is the object of this invention to produce a machine that is adapted to be employed in the manufacture of cushions and mattresses of any size and of the overstuffed or the other kind, and which will greatly facilitate the manufacture.

30 My invention can be most clearly described and will be most readily understood when reference is had to the accompanying drawings in which the preferred embodiment thereof is shown, and in which:

Fig. 1 is a top plan view of my machine with parts thereof broken away to better disclose the construction;

Fig. 2 is a side elevation of the machine shown in Fig. 1, a portion thereof being broken away;

Fig. 3 is a section taken on line 3—3, Fig. 1;

Fig. 4 is a perspective view of my machine at one period in its operation;

Fig. 5 is a section taken on line 5—5, Fig. 4, a portion of the casing being shown in place thereon;

Fig. 6 is a detail of the end member; and

Fig. 7 is a section taken on line 7—7, Fig. 4.

50 My machine comprises a frame having end pieces 1 and 2, top members 3 and 4 and bottom members 5, which form a rectangular structure to which the supporting members 6 and 7 are secured. Members 6 and 7 are substantially identical, each having a bot-

tom portion and sides 8 whose upper edges are turned inwardly to provide flanges 9 whose function will hereinafter appear. The supporting member 6 is rigidly secured to the frame as by bolts 10, but member 7 is 60 movable with respect to the frame. The bottom portions of both members 6 and 7 overlap in the manner clearly indicated in Figs. 1 and 3. Member 7 is adjustable with respect to member 6 and its position is determined by two doubled pitch screws 11 and 12 whose ends are journaled in the end pieces 1 and 2 and are rotated by cranks 13 and 14 respectively. Secured to the vertical side 8 of the member 7 are nuts 15 and 16 70 which cooperate respectively with the screws 11 and 12. It is now apparent that the operator, by means of the cranks 13 and 14, can rotate the screws 11 and 12 and thereby move member 7 with respect to member 6. 75 Since the screws 11 and 12 are connected to the member 7 at spaced distances, it is evident that by unequal rotation of the screws, the member 7 can be tilted with respect to the member 6 so as to be parallel therewith 80 or inclined with respect thereto. Slidably mounted in guides 17 carried by the transverse frame members 3 and 4 are racks 18 which are operatively related to the pinions 19 that are secured to the shaft 20. A crank 85 21 is secured to the shaft 20 and serves as the means by which it may be rotated for the purpose of reciprocating the racks. Secured to the forward ends of the racks is a sheet metal plunger head 22 whose cross-section 90 is somewhat channel-shaped and which extends transversely of the racks. An adjustable extension member 23 is connected to the member 22 by means which permits the two to be relatively adjusted. By rotating the 95 shaft 20 and pinions 19, the plunger head comprising the members 22 and 23 may be reciprocated. An end member 24 of channel-shaped cross-section has secured near one end thereof a pin 25 which is adapted to engage in an opening 26 in the side 8 of member 6. Secured to the other end of member 24 is an attaching means 27 comprising a 100 spring 28.

Let us now assume that the machine is 105 adjusted so that the parts assume the relations shown in Fig. 1 and that it is desired to make an overstuffed cushion whose size is substantially equal to the space between the sides 8, the end 24 and the plunger 110

members 22 and 23. A layer of cotton batting 29 (Fig. 7) is first laid on the supporting members and upon this layer 30 of hair. A spring assembly 31 is then placed upon 5 the layer of hair and on top of this I place a layer 32 of hair and a layer 33 of cotton. The space between the spring assembly and the sides, end and plunger is now stuffed with cotton or hair, as indicated by numerals 34. The plates 35 and 36 are then put in place with their outer edges underneath the inturned flanges 9 in the manner shown in Figs. 4 and 7. Pressure may now be exerted on the upper surface of plates 35 and 15 36 so as to compress the material underneath. For the purpose of holding the material compressed while the casing 37 is put into place, I provide a holding means consisting of a bar 38 which is held in adjusted position by means of a clamp 39. With the parts in the position shown in 20 Figs. 4 and 7, the end piece 24 is removed and by means of the screws 11 and 12 the sides 8 are moved together to the extent required to permit the casing 37 to be drawn 25 over the end of the machine to the position shown in Fig. 5. After the casing has been put into place, the screws 11 and 12 are operated to move the sides 8 apart until the 30 casing is stretched to some extent.

The operator now grasps the crank 21 and rotates the same in such a direction that the plunger moves outwardly, whereby the insides and the casing will be moved outwardly in a manner clearly apparent from the drawings. When the cushion has been 35

shoved entirely off from the machine by the plunger, the plates 35 and 36 are withdrawn from the cushion and the open side sewed up, which completes the same. 40

If the stuffing of the cushion or mattress is formed exclusively of hair or cotton, the material can be formed by superimposed layers which give better results than if the material were stuffed into the cushion in 45 the usual manner.

It is obvious that the machine can be made as large or as small as desired and may therefore be used for making small 50 cushions or large bed mattresses.

Having now described my invention, what I claim as new is:

In an upholstering machine, in combination, a frame, a supporting member comprising two parts, each of which has a bottom portion and a side portion, the bottom portions being overlapping, the side portions having their upper edges bent towards each other so as to form overhanging flanges, one of said parts having one end secured 60 to said frame, means for moving said parts towards and away from each other, a plunger slidably connected to said frame, means for reciprocating said plunger, and a top for said supporting member, said top consisting 65 of two separate plates adapted to overlap each other, one edge of each of said plates being adapted to project under said overhanging flanges.

In testimony whereof I affix my signature. 70

GEORGE N. ABBEY.
